Henry Williams

UNITED STATES PATENT OFFICE.

JOHN H. VINTON, OF BOSTON, MASSACHUSETTS, ASSIGNOR TO LOUIS C. SMITH, OF WINTHROP, MASSACHUSETTS.

PIPE-WRENCH.

No. 810,096.

Specification of Letters Patent.

Patented Jan. 16, 1906.

Application filed January 24, 1905. Serial No. 242,466.

To all whom it may concern:

Be it known that I, JOHN H. VINTON, a citizen of the United States, residing in Boston, in the county of Suffolk and State of Massachusetts, have invented certain new and useful Improvements in Pipe-Wrenches, of which the following is a specification.

This invention relates particularly to pipe-wrenches adapted for comparatively light work—such, for example, as is required in the care of automobiles; but I propose to employ it in any connection and either in light or heavy work.

The nature of the invention is fully described below and illustrated in the accompanying drawings, in which—

Figure 1 is a side elevation of my improved wrench. Fig. 2 is a side elevation of the same, the outer or covering portion of the movable jaw being illustrated in longitudinal vertical section. Fig. 3 is a perspective view of the outer or covering portion of the movable jaw removed. Fig. 4 is a cross-section taken on line 4-4, Fig. 1. In Figs. 1 and 2 a large portion of the bar is broken out.

Similar letters of reference indicate corresponding parts.

a represents the stationary jaw made integral with the bar or handle *b*. The inner or engaging face *c* of this jaw is at a slightly obtuse angle with the bar and is provided with inwardly-engaging teeth—that is, teeth pointing toward the bar *b*. The under or inner edge of the bar is provided with rack-teeth *d*.

The movable jaw comprises the main or working portion *e*, made, preferably, of cast tool-steel and having its engaging face *g* at an angle which is opposite to the angle of the face *c* of the stationary jaw when said jaws are in their normal position, as illustrated in Figs. 1 and 2. Thus the faces of the two jaws flare or produce a flaring opening, the faces being on divergent lines like the lines of a frustum. The engaging face *g* is provided with teeth pointing in the opposite direction from the teeth on the face *c*. This working or main portion *e* is embraced by a covering or yoke *h*, preferably of sheet-steel, consisting of two folds which unite at the upper edges and embrace the bar *b*, thus connecting the movable jaws slidably with the bar. This covering or yoke conforms to the shape of the portion *e*, completely covering its sides with the exception of a small portion next the face

of the jaw, and the two portions *e* and *h* constitute the movable jaw. Moreover, the working portion *e* completely fills the flanking portion of the covering or yoke with the exception of the small chambers left for the spring and worm, below described, thus providing a maximum of stock and strength for its position. The parts *g* and *e* are united by suitable bolts or rivets *k*.

In a vertical recess *l* in the part *e* of the movable jaw is set a spring *m*, which surrounds a pin *n* and lies between the head *p* of said pin and the bottom of the recess, whereby the inner or engaging end of the movable jaw is held normally away at a slight angle from the bar *b*, as shown.

In a horizontal recess *r* in the portion *e* is located a horizontally-disposed nut consisting of the cylindrical portion *s*, worm *t*, and shoulder bearings or trunnions *u*. Moreover, the cylindrical portion is provided centrally with an annular groove *v*. The nut has its bearings in the portion *e*, its cylindrical portion is in diameter of about the thickness of the portion *e*, and its thread or worm extends beyond the covering *h* and is suitably serrated or roughened, said covering or yoke being provided with openings *w* on the opposite sides, registering with the recess *r*. From the upper edges of the openings *w* downward extensions *y* enter the annular groove *v* and bear against the opposite sides of the nut within the groove, thus holding up the nut with its worm in engagement with the rack when the movable jaw *e* and yoke *h*, secured thereto, are swung down.

The nut which carries the worm is solid and of an integral piece, no pin being employed, and is held in place by the heavy shoulder bearings or trunnions *u*, whereby the said nut is rendered exceedingly strong and not liable to become broken. In assembling the parts it is dropped into position before the covering or yoke is applied, and as the trunnions occupy practically all the space between the two parts of said yoke shaking or rattling is prevented.

In operation when the wrench is applied to a pipe and the movable jaw pressed against it the oppositely-projecting teeth on the faces *c* and *g* grip firmly the opposite sides of the pipe, and as the bar *b* is operated the face *g* of the movable jaw moves a little inward toward the bar and its outer end of course

swings a little toward the face of the stationary jaw, whereby the angle of the face *g* is moved toward a right angle, reducing the flare of the opening, thus obtaining an exceedingly firm and powerful hold on the pipe.

10 In practice when the pipe is inserted between the jaws it is not pushed between them as far as it will go so as to touch the bar *b* in order to give the movable jaw an opportunity for the inward movement above described.

15 Should the movable jaw bring up against the bar, the bar operates as a stop and checks its further movement, thus preventing it from crushing the pipe. The extensions *y* operate in the well-known mechanical manner in connection with the worm to move the face *g* toward the face *e*.

20 Having thus fully described my invention, what I claim, and desire to secure by Letters Patent, is—

25 1. In a wrench of the character described, a bar or shank provided with rack-teeth on its under side and a stationary jaw integral therewith; a movable jaw comprising the yoke or covering *h* and the solid working portion *e* substantially filling said yoke or covering; and a solid nut provided with a worm engaging the rack-teeth and having trunnions integral with the nut held in place in the portion *e* by said covering *h*, substantially as set forth.

30 2. In a wrench of the character described,

a bar or shank provided with teeth on its under side, and a stationary jaw integral therewith; a movable jaw comprising the main or working portion *e*, and the yoke or covering *h* rigidly secured to the main portion and loosely embracing the said shank whereby the movable jaw can swing with relation to the shank; and a solid nut provided with a worm engaging the teeth and supported by said yoke or covering, substantially as set forth.

3. In a wrench of the character described, a bar or shank provided with rack-teeth on its under side and a stationary jaw integral therewith; a movable jaw comprising the yoke or covering *h* provided with the opposite openings *w* and with integral extensions *y* projecting into said openings, and a solid inserted working portion *e* provided with a recess substantially registering with and between said openings; and a nut provided with a suitable worm and having an annular groove *v* in its cylindrical portion into which the said parts *y* extend, said extensions *y* bearing against the opposite sides of the nut 60 within the groove *v*, and said nut being supported by the inserted portion *e* and with its worm extending through the opposite openings in the covering portion *h*, for the purpose 65 set forth.

In testimony whereof I have signed my name to this specification in the presence of two subscribing witnesses.

JOHN H. VINTON.
